SCREENING MILL

Charles F. Schutte and Herman D. Schutte,
Snyder, N. Y.

Application November 12, 1941, Serial No. 418,740

4 Claims. (Cl. 83—11)

This invention relates to screen mills, and more particularly to screen mills or pulverizers and improved means for mounting exchangeable screen members thereon.

One of the objects of the invention is to provide an improved pulverizer of the hammer mill type having improved means incorporated therein for mounting the product sizing screen member thereof. Another object of the invention is to provide a mill of the character described having an improved form of product screening element which is adapted to be mounted and demounted with respect to the mill frame in an improved manner. Another object of the invention is to provide in a mill of the character described improved means for detachably locking the product screening member in mounted position relative to the mill frame. Another object of the invention is to provide a mill of the character described having an improved arrangement for quickly and easily exchanging product screening members thereof so as to grade the mill product to different specification. Another object of the invention is to provide a mill for the purposes set forth hereinabove wherein the procedure of exchanging the screen members thereof may be performed with improved facility and without requiring the mill to be first shut down. Other objects and advantages of the invention will appear in the specification herein-after.

In the drawings:

Fig. 1 is a side elevation of a hammer mill of the invention with a portion of the casing broken away to show the interior thereof, and with the screen member thereof shown in both mounted and demountable positions;

Fig. 2 is a perspective, on an enlarged scale, of a portion of the screen positioning and locking mechanism thereof;

Fig. 3 is a fragmentary top plan of the machine of Fig. 1;

Fig. 4 is a section taken substantially along line IV—IV of Fig. 3; and

Fig. 5 is an enlarged view of a detail of Fig. 1, showing the screen positioning and latching mechanism in different positions of operation.

The drawings illustrate the invention in connection with a hammer mill of the type that is adapted particularly for grinding or pulverizing any commodity, and the mill comprises essentially a box-like base or frame 10 carrying bearing blocks 12 at opposite sides thereof for rotatably supporting the rotor shaft 14. The rotor 16 is carried by the shaft 14 and in turn

5 mounts a series of hammers 18 which are pivotally connected to the rotor so as to extend radially therefrom. Heads 20 are carried by the hammers 18 to receive the majority of the wear in connection with processing of the mill feed. An upper casing or cover portion 22 is mounted upon the base 10 so as to complete the mill enclosure, and a mill feed inlet spout 24 is arranged to discharge the mill feed through an inlet port 26 of the mill cover so as to discharge the mill feed in the form of a continuous stream into the mill casing and upon the rapidly rotating rotor and hammer unit while traveling in substantially the same direction of movement.

10 The end wall portion of the mill casing substantially opposite to the mill feed chute is preferably reinforced by a wearing plate 30 in the region of impingement of the mill feed stream against the casing wall resulting from the momentum of the mill feed and the impact of the rotor hammers thereagainst. Thus, the wearing plate 30 may constitute an integral portion of the mill casing, or may be simply a detachable wearing plate mounted therewith so as to be renewed from time to time as may be required. In any case it will be understood that the end wall portion 32 of the mill casing will preferably be of curvilinear form and shaped to complement as closely as possible the circular orbit 15 of the hammer heads 20 as the rotor revolves. However, due to the necessity of providing the mill feed inlet arrangement as shown and described, the casing wall 32 must necessarily withdraw from the orbit of the mill hammers in the region of the mill feed inlet port. Thus, the casing wall portion 32 will be of progressively 20 flattening curve form from the approximate elevation of the rotor shaft 14 to the region of the mill feed inlet port.

25 In conformity with established principles of preferred hammer mill construction the product screening element of the mill comprises an accurately shaped screen member such as a perforated sheet metal plate or a woven wire fabrication, or the like, and the screen member is mounted to extend transversely of the mill frame structure 10 between opposite side wall portions thereof and so as to complement and closely conform to the lower arc of the mill hammer orbit. Consequently, in the case of certain mills of the prior art the screen elements thereof corresponding to the member 34 of the present invention are arranged to be mounted relative to the other mill elements when in operative position so as to be disposed in substantially the same manner of

arrangement as is illustrated by Fig. 1 of the present drawing. However, the prior art arrangements usually involve in addition some provision for dropping the screen member downwardly away from operative position preliminary to removal of the screen member from the mill frame in connection with screen exchange procedures as are required to turn out products of various specifications. Such arrangements have invariably involved the use of relatively complicated screen support and exchange devices; the use of which usually requires the mill to be stopped before the screen members may be exchanged, and through use of which the time required for screen exchange is very substantial. In any case, the necessary procedure for exchanging the screening elements of such prior art mills requires substantial time losses and is accompanied by substantial mechanical difficulties and inconveniences or other disadvantages.

In accord with the present invention the opposite side wall portions of the base frame 10 are provided with inwardly extending ledges 36 which are of substantially circular form in side view and disposed concentrically of the center of rotation of the rotor-hammer unit. A second set of inwardly extending ledges 38 are arranged to extend inwardly from the side wall portions of the base frame and are arranged in substantial parallelism with and are relatively closely spaced relative to the corresponding ledges 36 in the region of the rear half of the mill. Thus, a relatively narrow space as indicated at 40 is provided between the corresponding ledge members 36-38 at each side of the mill in the rear portion thereof for slide-fitting reception of the corresponding side edge portions of the screen member 34 therebetween. Thus, it will be understood that in the rear portion of the mill the ledge members 36-38 at opposite side wall portions of the mill frame will cooperate to position the rear portion of the screen 34 in operative position and in an attitude of concentricity with respect to the axis of the rotor rotation.

At the forward end portion of the mill, however, the ledge members 38-39 are formed so as to diverge from the positions of the corresponding ledge members 36 so as to provide a funnel-like space as indicated at 42 (Figs. 1 and 5) between corresponding of the ledges 36-38 within which the corresponding end portion of the screen member 34 is free to move in directions radially of the axis of rotor rotation. The screen member 34 is formed to be of resilient nature and to have a tendency to "set" in a curvature having a radius substantially larger than the radius of the orbit of the hammer mill rotation.

Thus, any one of a number of the screen members 34 of the invention is adapted to be selected and mounted singly within the mill by initially disposing it in pick-a-back relation upon the casting wall 32 as illustrated by broken lines in Fig. 1. Then the lower end of the screen member is inserted into the funnel-like spaces between the ledges 36-38, whereupon the screen member may be slid downwardly and under the rotor hammer assembly as its leading end portion processes rearwardly of the mill and is guided between the closely spaced ledges 36-38 into final operative position. During this initial installation procedure the trailing end portion of the screen 34 will of course bear away from the inner ledges 36-36, due to the tendency of the screen member to normally set at a curvature somewhat flatter than the curvature

of the ledges 36. The screen positioning and locking mechanism of the invention is then brought into action to complete the installation of the screen member in operative position.

5 The positioning and locking member comprises essentially a lever device including a forward blade portion 50 having a handle 52 extending rearwardly therefrom. The forward edge of the blade 50 is formed with a beaded nose 54 so as to engage in roller bearing contact relation beneath a laterally extending flange portion 56 of the screen. It will be understood that the flange portion 56 of the screen may be conveniently provided by margining the trailing end portion of the screen with a stock angle iron, as illustrated in the drawings, or by simply turning a flange on the end of the screen plate, or by any other suitable means. The blade of the locking device is formed to extend rearwardly into a heel portion 58 which is adapted to be brought to bear downwardly upon a fixed edge portion 60 of the mill casing. Thus the rear end of the handle 52 may be thereupon pressed downwardly so as to rotate the nose end 54 of the blade upwardly, 10 while at the same time the blade is pushed in the direction of the mill so that the trailing end portion of the screen is thereby moved against the elastic force thereof so as to move from the solid line position thereof of Fig. 5 toward the broken line position thereof, whereupon the screen member 34 will be disposed entirely against the ledges 36-36 throughout the length of the screen.

15 A guide bracket 62 is provided to extend from the fixed ledge portion 60 at each of the opposite sides of the mill so as to be adapted to engage against the heel portion of the blade 50 at opposite sides thereof in such manner as to positively position the blade 50 in relation to its distance from the mill. The bracket portions 20 62-62 are diagonally disposed in plan view as illustrated in Fig. 3 to cooperate with suitably cut end portions 64-64 of the blade 50 in such manner that the brackets 62-62 function simultaneously to position the blade in directions to 25 and from the mill and in directions laterally thereof.

20 A pair of side arms 66 are mounted to extend in spaced relation forwardly of the mill casing and to carry at their ends a transverse bar 68 upon which is mounted a clamp 70 having an upper end portion adapted to clamp over the handle 52 of the screen lock blade 50 so as to prevent the blade 50 from rotating out of engagement behind the brackets 62 while the mill is in operation. The clamp 70 carries a set screw 72 arranged to be manually adjusted by means of a knob 74, whereby upon final clamping of the screen 34 in operative position the clamp 70 may be firmly locked against unintended disengagement from the blade handle 52.

25 Thus, it will be understood that whenever it becomes necessary to exchange the screen of the mill the locking clamp 70 will first be disengaged from the handle 52; the handle 52 will then be lifted as to the solid line position of Fig. 5 whereupon the adjacent end of the screen 34 will move into the funnel-like space between the opposed ledges 36-38 in response to the elastic forces of 30 the screen material. The free end of the screen may then be grasped by the operator of the mill and the screen withdrawn by simply lifting it upwardly as to the broken line position thereof in Fig. 1, whereupon the screen may be removed completely from the mill and a substitute screen

of generally similar form but having the required sized apertures may be inserted, as in the manner of mounting described hereinabove. It will be appreciated that a particular feature and advantage of the arrangement of the invention resides in the fact that due to the natural resiliency and tendency of the screen members to open to curvatures of greater diameter than the curvature of the mill rotor orbit when the screens are released from restraint against the ledges 36-38, the screen members will be thereby automatically adapted to move freely about the enlarged curvature of the end wall 32 of the mill casing. Otherwise, the screen members would clamp and wedge against the end wall 32 of the casing in such manner as to prevent the mounting and dismounting procedure as described hereinabove. It will also be appreciated that the screen positioning and locking mechanism of the invention provides, in combination with the other elements of the device, an improved method and means for quickly and positively positioning and locking the screen in operative position upon the mill, and for quickly releasing the screen in connection with dismounting operations; and that the entire screen exchange procedure may be accomplished in only a few seconds while the mill rotor is kept running. Thus, much valuable time which would otherwise be lost in connection with the screen changing process is saved.

It will also be appreciated that in view of the novel arrangement and operation of the machine of the invention the screen exchange process may be conducted without possibility of danger to the operator of the machine, and with utmost facility and convenience to the operator thereof in every respect; and that although only one form of the invention has been shown and described in detail, it will be apparent to those skilled in the art that the invention is not so limited but that various changes may be made therein without departing from the spirit of the invention or the scope of the appended claims.

What is claimed is:

1. In a sizing mill, a bottom frame, a rotor mounted upon said frame for rotation within a circular orbit, a semi-cylindrical screen mounted upon said frame to substantially complement the lower half of said rotor orbit, said screen being elastic and having a tendency to normally set in a curvature having a radius substantially greater than the radius of said rotor orbit, a cover mounted upon said bottom frame to complete enclosure of said rotor at the upper side thereof, said cover being shaped to generally conform to the orbit of said rotor but to diverge therefrom to provide an enlarged space therebetween to receive the mill feed, upper and lower coacting ledge means extending from said bottom frame to slidably receive and position one end portion of said screen so as to be concentric with said rotor orbit and in continuation of the adjacent portion of said cover, and lever means adapted to be detachably mounted upon said frame at the opposite end thereof and to be actuated manually for levering the other end of said screen against the elastic forces thereof into a position of concentricity with respect to said rotor orbit and in continuation of the adjacent portion of said cover, and locking means associated with said screen levering means for detachably locking the latter in operative position, said upper and lower ledge means being disposed in relatively closely spaced relation at the rear portion of said mill for fixing said screen concentrically of said rotor orbit.

5 of said rotor orbit at the rear portion of said mill, and said lower of the ledge means being arranged to diverge away from the upper of said ledge means at the forward portion of said mill to provide therebetween a space to permit said screen to expand in cantilever supported relation toward its normal set attitude when said lever means is detached therefrom.

2. In a sizing mill, a bottom frame, a rotor mounted upon said frame for rotation within a circular orbit, a semi-cylindrical screen mounted upon said frame to substantially complement the lower half of said rotor orbit, said screen being elastic and having a tendency to normally set in a curvature having a radius substantially greater than the radius of said rotor orbit, a cover mounted upon said bottom frame to complete enclosure of said rotor at the upper side thereof, said cover being shaped to generally conform to the orbit of said rotor but to diverge therefrom to provide an enlarged space therebetween to receive the mill feed, upper and lower coacting ledge means extending from said bottom frame to slidably receive and position one end portion of said screen so as to be concentric with said rotor orbit, and lever means adapted to be detachably mounted upon said frame at the opposite end thereof and to be actuated manually for levering the other end of said screen against the elastic forces thereof into a position of concentricity with respect to said rotor orbit, and locking means associated with said screen levering means for detachably locking the latter in operative position, said upper and lower ledge means being disposed in relatively closely spaced relation at the rear portion of said mill for fixing said screen concentrically of said rotor orbit at the rear portion of said mill, and said lower of the ledge means being arranged to diverge away from the upper of said ledge means at the forward portion of said mill to provide therebetween a space to permit said screen to expand toward its normal set attitude when said lever means is detached therefrom, whereby said screen may be mounted in operative position within said mill by disposing it in inverted attitude upon said cover and then sliding said screen downwardly and under said rotor into engagement with said ledge means at the rear end of said mill, and then levering the trailing end portion of said screen into constricted curvilinear form against the elastic force of said screen into an attitude of concentricity with respect to said rotor orbit and locking said screen in said operative position by means of said locking means, and whereby said screen may be replaced by another screen of generally similar form by first releasing said locking means to allow said screen to expand so as to be adapted to slide relative to said cover in freely encompassing relation thereagainst for slidably withdrawing said screen upwardly out of said mill preliminary to similar mounting of the replacement screen.

3. In a screening mill, a lower frame member supporting a hammer mill rotor thereon, a cover member of generally circular sectional form mounted upon said frame to complete enclosure of said mill, said cover being of a sectional curvature of greater radius than the radius of the orbit of said rotor, a semi-cylindrical screen member formed of elastic material to have a natural set in a curvature of a radius greater than the radius of said rotor orbit, means for cantilever mounting one end portion of said screen upon said frame in predetermined spaced relation with

respect to said rotor orbit, and lever means adapted to engage beneath and actuate the other end portion of said screen upwardly and into similarly spaced relation with respect to said rotor orbit against the elastic force of said screen, said lever device comprising a spade-like member having a plate portion with a rounded nose adapted to engage beneath a laterally flanged end portion of said screen and a plate heel portion adapted to bear upon said frame and a handle portion extending rearwardly therefrom for levering said screen into operative position, and bracket means extending from said frame for cooperation with said plate heel portion to position said lever member relative to said frame during said levering operation, whereby said lever device may be removed to provide a screen removal opening and to simultaneously permit said screen to become relaxed into free sliding condition relative to said mounting means and relative to said cover so as to be readily slipped out of said removal opening and arcuately upwardly over said cover in pickaback relation thereon.

4. In a screening mill, a lower frame member supporting a hammer mill rotor thereon, a cover member of generally circular sectional form mounted upon said frame to complete enclosure of said mill, said cover being of a sectional curvature of greater radius than the radius of the orbit

of said rotor, a semi-cylindrical screen member formed of elastic material to have a natural set in a curvature of a radius greater than the radius of said rotor orbit, means for cantilever mounting one end portion of said screen upon said frame in predetermined spaced relation with respect to said rotor orbit, and lever means adapted to engage beneath and actuate the other end portion of said screen upwardly and into similarly spaced relation with respect to said rotor orbit against the elastic force of said screen, said lever device comprising a spade-like member having a plate portion with a rounded nose adapted to engage beneath a laterally flanged end portion of said screen and a plate heel portion adapted to bear upon said frame and a handle portion extending rearwardly therefrom for levering said screen into operative position, and bracket means extending from said frame for cooperation with said plate heel portion to position said lever member relative to said frame during said levering operation, said bracket members being disposed diagonally of the axis of said mill and adapted to coact with correspondingly beveled portions of said plate heel so as to simultaneously position said covering member in directions longitudinally of said mill and transversely thereof.
